BEIRNE GORDON, JR., OF UTICA, NEW YORK, ASSIGNOR TO SKENANDOA RAYON CORPORATION, OF UTICA, NEW YORK, A CORPORATION OF NEW YORK

MANUFACTURE OF ARTIFICIAL SILK

Application filed March 20, 1930. Serial No. 437,301.

This invention relates to the manufacture of artificial silk, and more particularly to a new and improved process of winding the yarn after it has been spun, and to apparatus for performing the same.

An object of the invention is to provide a new and improved process of manufacturing artificial silk. A further object of the invention is to provide a new, advantageous and simplified process of and apparatus for winding yarn from a yarn cake onto a bobbin. Other objects and advantages of the invention will appear from the following description.

The invention will be hereinafter particularly described as applied to the viscous process of manufacturing artificial silk, it being understood however that the application of the invention is not necessarily limited to this process, but may, under some conditions, extend to certain other processes for the manufacture of artificial silk.

In the manufacture of artificial silk by the viscose process, according to the pot spinning method, the procedure heretofore generally used has been as follows:

Properly prepared, filtered, deaerated and ripened viscose is ejected under pressure in the form of a plurality of streams from the orifices of a spinnerette into a spinning bath where it is coagulated into a corresponding number of very fine filaments. These filaments, after coagulation by the action of the bath, are led by means of suitable guides from the bath up over a Godet wheel and thence down through a reciprocating "traversing funnel" into a rapidly rotating spinning pot. The filaments are spun or twisted into yarn by the rotation of the pot, and the spun yarn is thrown outwardly by the centrifugal force of the rotation, against the interior wall of the pot, where it forms a yarn "cake". This cake is annular in form and consists of a very large number of helically wound layers of yarn. The height of the cake is controlled by the distance of movement of the traversing funnel, which is regulated so as nearly to equal the depth of the spinning pot, and the thickness of the cake depends upon the time of spinning.

The cake consists of coagulated and partially regenerated fibrous material derived from the viscose in the proportion of roughly 25% by weight of the cake, and salts, acid and water derived and carried over from the spinning bath and constituting the remaining weight of the cake. The cakes so spun are next doffed from the spinning pot, and are aged for a suitable time whereby regeneration of the cellulose from the viscose is completed by the salts and acid remaining in the cake. After ageing is completed the yarn from the cakes is reeled into skeins, in which form it is subjected to the numerous subsequent treatments, such as washing, desulphuring, bleaching, soaping, and so forth, which are necessary or desirable for the production of commercial yarn.

That process has been found to possess a number of disadvantages and difficulties, among which may be enumerated the deterioration of the yarn which occurs in and because of the reeling and skeining operation; the deterioration which occurs during subsequent treatment of the yarn while in skein form; the degradation of the yarn which occurs during backwinding of the skeins into packages suitable for fabrication; and the difficulties introduced by the desirability of matching the schedule of the skeining and subsequent first washing operation to the spinning schedule in order to produce a uniform ageing of the spun yarn. This latter difficulty is accentuated by the fact that in ordinary operation the spinning is continuous, being carried out on a twenty-four hour day, seven day week schedule, while the reeling and skeining, which must precede the first washing (which washing alone terminates the ageing of the spun yarn), is carried out in a single shift of, say, seven hours a day and five or six days a week.

To avoid or minimize the foregoing and other difficulties it has been found desirable under certain conditions to wind the yarn from the cake onto a perforated bobbin, on which all subsequent treatment or "processing" of the yarn may be carried out. Thus washing, desulphuring, bleaching, soaping, and other desired solutions may be suc-

sively introduced under pressure into the interior of the perforated bobbin, whence they pass outwardly through the yarn and perform their respective functions at once more readily and conveniently, and with less injury to the yarn, than if these same treatments were performed upon the yarn in skein form.

In this process of treating the yarn in which it is wound from the cake onto a perforated bobbin, it has been proposed to wind the yarn directly from the cake onto the bobbin, without any previous treatment of the yarn. In this case the yarn package on the bobbin contains a high percentage of salts and acid from the spinning bath and must be very tightly wound if injurious loosening of the package after removal of the salts is to be avoided. I have, however, found it advantageous, under many circumstances, to subject the spun cake to prewashing in cake form, in order to remove the contained salts and acid derived from the spinning bath. This prewashing of the cake affords certain advantages, of which the following are examples: The ageing of the spun yarn may be regulated to a predetermined period without any necessity of matching a spinning schedule to a skeining schedule, it being only necessary to wash the cake without any intervening step in order thereby to terminate the ageing at a desired and controlled instant; the yarn package, when the yarn has been wound onto the perforated bobbin, is free from salts and acid, and the necessity for a tightly compacted yarn package and the danger of loosening of the package upon removal of the salts, with consequent injury to the yarn, are alike obviated.

In conjunction with either of the foregoing processes, that is whether prewashing be employed or not, I have heretofore proposed to wind the yarn from the cake onto a perforated bobbin by means of a special process and winding machine which I have developed for the purpose, and this process and machine are described and claimed in my copending application for Letters Patent of the United States Serial No. 327,611, filed December 21, 1928. Although in many cases this winding process and machine is admirably suited to its purpose, I have now found that under certain circumstances I can perform the winding from the cake to the bobbin ever more advantageously in the manner, and by means of the machine, which I shall now describe in connection with the accompanying drawings, in which:

Figure 1 is a view partly in section and partly in elevation of a portion of one form of machine upon which my new process of winding from the cake to the bobbin may be performed, and which will be described by way of example, and

Figure 2 is a partially diagrammatic view 65 of a machine for carrying out my winding

process, showing an example of one form of driving mechanism for operating the same, and

Figure 3 is a section on the line A—A of Figure 2.

Referring more particularly to Figure 1, a cake-holding "winding pot", 1, is provided with a circular aperture, 2, in its base, 3. This aperture is of sufficient diameter to permit the passage of a bobbin wound with the desired amount of yarn, but is preferably of the same diameter as, or of less diameter than, the inside bottom diameter of a full yarn cake, a nearly full cake being shown at 17. The pot, 1, is attached either integrally or by means of a suitable clamping or locking means, 3', to, and supported by, a hollow cylindrical spacing sleeve, 4, provided with an upper annular flange, 5, which engages the base, 3, of the pot 1, and with a base, 6, which engages the vertical shaft, 7, of an electric motor or other suitable means (not shown) for rotating the pot, 1. The shaft, 7, is supported and prevented from whipping by means of the bearing assembly, 8, which should be constructed so that the cylindrical spacing sleeve, 4, and the pot, 1, when rapidly rotated by the shaft, 7, are free from unbalance and vibration, which might break the thread during winding.

The spacing sleeve, 4, is of such internal diameter and depth as readily to receive interiorly a bobbin of the desired size, wound with the desired quantity of yarn, preferably the yarn content of at least one yarn cake. Thus the inside diameter of the sleeve is suitably the same as that of the aperture, 2, and its depth is slightly greater than the length of a bobbin.

A hollow perforated bobbin, 9, of the desired size, is supported on the vertically depending bobbin-support or mandrel, 10, arranged concentrically with the axis of the pot, and is locked by means of the clamping ring, 11, provided with a stud, 11', which engages the bayonet-lock slot, 12. The bobbin-support, 10, is mounted on a horizontal arm, 13, which is slidably mounted on the vertical guide shaft, 14, by means of the bushing, 15.

A slow downward motion is imparted to the arm, 13, by the feed-screw, 16. This screw may be automatically driven from the shaft, 7, by means of a worm gear or other suitable reduction mechanism, not shown in Fig. 1. A rapid reverse drive or other suitable means is also preferably provided for restoring the arm, 13, to its original elevated position, and a clutch may also be provided if desired.

To perform the winding operation, the arm, 13, is raised to its upper position, so that the mandrel, 10, is clear of the pot, 1; an empty bobbin is placed and locked on and to the mandrel, so that it is coaxial with

the pot, 1; a yarn cake, 17, is placed in the pot, 1; the inner end of the yarn is tied or wound around the lower end of the bobbin; and the bobbin is lowered into the starting 5 position, i. e., with the lower end of its winding space opposite the bottom of the cake. The shaft, 7, is then set in rotation, and the yarn is rapidly unwound from the rotating yarn cake and wound directly onto the bobbin. The cake having been originally wound while a traverse motion was being imparted to the yarn, a corresponding traverse motion is automatically imparted to the yarn as it is unwound from the cake and 10 wound onto the bobbin. The feed mechanism, 16, imparts a slow downward axial motion to the bobbin past the cake, and the combination of this slow axial feed of the bobbin with the traverse of the yarn as it is unwound from the cake and wound onto the bobbin produces on the bobbin a yarn package of the "barrel" or tapered-end shape which I have found to be especially suitable 15 for washing and other treatment.

25 One suitable form of machine for performing the winding operation is shown in Figure 2, in which like reference characters denote like parts to those shown in Figure 1. In addition to the elements shown in Figure 30 1, Figure 2 shows one suitable form of driving mechanism. The motor 18, is connected to the shaft, 19, which carries slidably mounted thereon the friction wheel, 20. When this friction wheel is moved to the left 35 it engages the smaller friction wheel, or disc, 21, which is mounted on and drives the shaft, 7, carrying the sleeve, 4, and spinning pot, 1. The small pinion, 22, carried on the same shaft, engages a gear, 23, which is secured to 40 and drives the feed-screw, 16, at a relatively slow rate, thereby feeding the bobbin, 9, downwardly through the pot, 1. A clutch, 24, is arranged to be operated by the linkage, 25, 26, 27, 28, and is so arranged that 45 when the clutch member, 29, is moved into engagement with the clutch member, 30, the friction wheels, 20, and 21, are automatically disengaged, and a rapid reverse drive is imparted to the feed-screw, 16, by means of 50 the large bevel gear, 31, which engages the small bevel gear, 32, on the bottom end of the screw shaft, 16. During this reverse drive, the pinion, 22, is disengaged from and idles around the shaft, 7, by virtue of a 55 ratchet such as that shown in Figure 3, which is a section taken on the line A—A, of Figure 2.

The arm 13 may be provided with a lug 60 13a arranged to engage the lugs 28a and 28b mounted on the clutch operating rod 28. Thus when the lug 13a engages the lug 28b, at the bottom of the downward travel of the bobbin, it operates the clutch linkage so as to disengage the friction wheels 20 and 21, engage the clutch members 29 and 30, and 65 start the reverse drive of the feed-screw 16. Before this is done, the yarn cake should preferably be wholly unwound, and the yarn entirely wound onto the bobbin. To prevent this automatic reversal of the drive, in case it is not desired, the intermediate stop or yoke 27a is provided for bell-crank lever 27, so that the clutch is moved only so far as the neutral position and the drive is stopped. By withdrawing the yoke 27a, 70 the clutch is then again automatically engaged and the reverse drive started. At the upper limit of travel of the arm 13, carrying the bobbin 9, a like function is performed by the lug 28a, when engaged by the lug 13a. This reversal is automatic if the yoke 27a is left withdrawn, or if the yoke 27a is replaced, the engagement of lug 13a with lug 28a merely moves the clutch 24 to the neutral position, and thus stops the 75 drive. The hand-wheel, 33, may also be used at will for adjustment of the feed-screw, 16, to position the bobbin.

An advantage of this direct winding process, which for convenience I have termed "pot-winding", is that friction affecting the 80 yarn is almost entirely avoided, since the use of guides and feeds for the yarn, which have been hitherto necessary, is entirely avoided by my new process. In previous winding processes and apparatus it has been necessary to feed the yarn from the cake over a series 85 of guides, and through traverse mediums, to the bobbin, and this has involved, also, a change in direction of travel of the yarn. The friction to which the yarn was thus subjected during the winding frequently produced injury and consequently decreased production of grade "A" yarn. In former winding processes, moreover, the speed of winding 90 was limited by the mechanical movements employed, by the increased likelihood of injury to the yarn at high speeds, and by other physical limitations of the apparatus. In 95 the present process, on the contrary, it has been found that very high winding speeds can be attained, particularly if the rotating parts of the apparatus are in nice dynamic balance so that whipping is avoided, in which 100 case, winding speeds of many thousands R. P. M. may be employed, and great economy of time effected. Still another advantage of the present invention is that a substantially uniform tension on the yarn can 105 be maintained, while winding it onto the bobbin, resulting in a much more uniform. 110 quality of yarn. Further, the angle at which the yarn is wound onto the bobbin can also be maintained more nearly uniform, which 115 also results in an improved product. These and other advantageous results may be accomplished, in apparatus such as that described, by proper design and proportioning 120 of the apparatus and inter-adjustment of its 125 130

elements. Thus the size of the pot, cake and bobbin, the relative rates of rotation of the cake and axial movement of the bobbin, and shape of the several elements, are factors 5 which may be considered in this connection, as will be readily understood by persons skilled in this art.

The present invention may be applied to produce a wide variety of desirable results in 10 addition to those already mentioned. For example, in my co-pending application, Serial No. 449,133, filed May 2, 1930, I have described and claimed a process and apparatus whereby rayon may be "processed", and its 15 manufacture into dry finished yarn completed, in cake form. The present invention may be advantageously employed for winding such dry, processed rayon onto a bobbin, either for drying or for fabrication. Instead 20 of an ordinary hollow perforated bobbin, such as that shown at 9 in the drawings, I may, particularly in the last mentioned case, employ a paper or other suitable tube, and wind the rayon from the cake onto that tube 25 instead of a bobbin, in which condition it may be sold.

During the process of winding from a cake onto the bobbin, in the event that the cake is still wet, for example if it has recently 30 been washed, the transfer from the cake to the bobbin according to the present invention may also simultaneously be used to dry the cake by means of centrifugal force or hydro-extraction.

35 Other applications and uses of the present invention may be devised by persons skilled in the art, and the present invention is not limited to the specific examples of the process and apparatus described herein. For example, 40 it is possible that my process, at least in some of its phases, might be carried out, and that some of its advantages might be realized, by rotating the bobbin within the cake, rather than by rotating the cake about 45 the bobbin, or by rotating both the cake and the bobbin, either in opposite directions, or in the same direction at different speeds. Of course the winding pot or cake container, 1, can, if preferred, be made integral with the 50 driving motor or shaft, in order to avoid a gear connection or friction drive at that point. These and other variations of the specific arrangements described herein, may fall, therefore, within the spirit of my invention.

55 What is claimed is:

1. Process of manufacturing artificial silk, which comprises, in combination, the steps of ejecting a plurality of streams of viscose 60 from the orifices of a spinnerette into a spinning bath; coagulating the ejected viscose streams into a plurality of filaments; twisting the filaments into yarn and winding the yarn into a cake by passing the co- 65 agulated filaments into a rotating spinning

pot; placing the spun yarn cake in a winding pot provided with an aperture in the bottom thereof of larger diameter than the outside of a wound bobbin, and arranging the same coaxially with a bobbin upon which the yarn 70 is to be wound; and winding the yarn directly from the yarn cake onto the bobbin by attaching the inner end of the yarn to the bobbin and imparting a rotary motion to the yarn cake while producing a relatively 75 slow axial movement of the bobbin with respect to the yarn cake through the aperture in the bottom of the winding pot.

2. Apparatus for winding artificial silk 80 yarn from a yarn cake onto a bobbin, comprising, in combination, a winding pot adapted to receive a yarn cake and provided with an aperture in the bottom thereof of greater diameter than a wound bobbin; a shaft for rotating said winding pot, means for supporting a bobbin interiorly of said winding pot and coaxially therewith, and means for moving said bobbin axially downward through said pot and aperture while winding the yarn 85 from said cake onto said bobbin.

3. Apparatus for winding artificial silk 90 yarn from a yarn cake onto a bobbin, comprising, in combination, a winding pot adapted to receive a yarn cake and provided with a bottom aperture larger than the diameter of a wound bobbin; a hollow sleeve arranged coaxially below said winding pot and engaging and supporting the same, and adapted to receive a wound bobbin of yarn; a bobbin; means for supporting said bobbin interiorly of said pot and sleeve and coaxially therewith; means for rotating said pot and sleeve; and means for moving said bobbin endwise along the common axis of said pot, sleeve and bobbin during said rotation; whereby yarn 95 from a yarn cake contained in said pot is unwound from said cake and wound onto said bobbin and is distributed along said bobbin during the winding thereof.

4. In an apparatus for winding artificial 100 silk from a yarn cake onto a bobbin, the combination of a winding pot adapted to receive a yarn cake and provided with a bottom aperture of larger diameter than the diameter of a wound bobbin; a hollow sleeve arranged coaxially below said winding pot and engaging and supporting the same and adapted to receive a wound bobbin of yarn; a bobbin; means for supporting said bobbin interiorly thereof and coaxially therewith; means for rotating said pot to perform the winding operation; means for imparting to said bobbin a relatively slow downward movement along the axis of said pot, sleeve and bobbin during said rotation, whereby yarn 105 from a yarn cake contained in said pot is unwound from said cake and wound onto said bobbin and is distributed along said bobbin during the winding operation; and means 110

115

120

125

130

for imparting a relatively rapid reverse movement to said bobbin along said common axis, when the winding operation has been completed.

5. In an artificial silk winding machine the combination of a winding pot provided with an aperture in the bottom thereof; a hollow sleeve arranged coaxially below said pot and in engagement with the bottom thereof; a shaft for rotating said sleeve and pot; a motor for driving said shaft; a bobbin; means for supporting said bobbin coaxially with said pot and sleeve; a feed-screw driven by said shaft for imparting a relatively slow axial movement to said bobbin with respect to said pot; and means for disengaging said pot from said driving shaft and imparting a relatively rapid reverse motion to said feed-screw.

20. 6. The method of unwinding yard from a yarn cake directly onto a bobbin extending through the yarn cake which comprises relatively rotating the yarn cake and bobbin to unwind the yarn from the yarn cake and wind it directly upon the bobbin; and relatively moving the yarn cake and bobbin longitudinally of the axis of rotation through a distance greater than the height of the yarn cake, while the yarn is being wound off of the 25 yarn cake onto the bobbin, to present a winding length on the bobbin in excess of the height of the yarn cake.

7. The method of unwinding yarn from a yarn cake directly onto a bobbin extending through the yarn cake which comprises rotating the yarn cake while constraining the bobbin against rotation, to unwind the yarn from the yarn cake and wind it directly upon the bobbin; and moving the bobbin along the 30 axis of the yarn cake through a distance greater than the height of the yarn cake, while the yarn is being wound off of the yarn cake onto the bobbin, to present a winding space on the bobbin of greater length than 35 the height of the yarn cake.

8. The method of unwinding yarn from a yarn cake directly onto a bobbin extending through the yarn cake which comprises rotating the yarn cake to unwind the yarn therefrom and wind it directly upon the bobbin; and, during the course of winding the 40 yarn thereon, moving the bobbin axially through the yarn cake through a distance greater than the height of the yarn cake.

55. 9. A machine of the class described comprising in combination; a pot adapted to receive a hollow yarn cake, a bobbin movable through the pot and a contained yarn cake 50 and adapted directly to receive yarn progressively unwound from the inside of the yarn cake, the bobbin having a winding space longer than the height of the yarn cake to be unwound, means for rotating the pot to 60 cause the yarn to be unwound from the yarn 65

cake directly onto the bobbin, and means for moving the bobbin through the pot.

10. Method of winding a bobbin of yarn to produce a tapered-end barrel-shaped yarn package in which the yarn is distributed over a relatively long winding space on the bobbin in a relatively thin layer, whereby the yarn package on the bobbin is well adapted for processing thereon by means of liquid forced through the bobbin, or for other operations, 70 in which the yarn is first wound into a yarn cake by rotation of the cake and vertical reciprocating traverse of the yarn, and the yarn is then unwound from the yarn cake and wound onto the bobbin while they are coaxially disposed with the bobbin inside the cake, and producing a continuous relative longitudinal movement in one direction only of the yarn cake and bobbin along their common axis during the winding operation, 75 through a distance greater than the height of the yarn cake, whereby the traverse of the yarn previously wound into the yarn cake automatically produces a substantially equal traverse of the yarn as it is unwound from 80 the cake onto the bobbin, which traverse is superposed, during the winding of the bobbin, on the greater unidirectional relative axial movement of the yarn cake and bobbin, and the winding space on the bobbin to which 85 the yarn is being applied consequently progresses along the length of the bobbin during the entire winding operation through a distance greater than the height of the yarn cake, said winding space being at any one instant 90 constantly substantially equal to the height of the yarn cake, to produce a yarn package on the bobbin having the said tapered-end barrel-shaped form with the yarn distributed over a winding space on the bobbin relatively longer than the height of the 95 yarn cake, and in a relatively thin layer.

In testimony whereof I hereto affix my signature.

BEIRNE GORDON, JR. 110
